SHOWER CURTAIN HOLDER

Jack Sherman, Brooklyn, N. Y.

Application February 13, 1939, Serial No. 256,125

3 Claims. (Cl. 156—20)

This invention relates to shower-bath curtain installations, and particularly to means designed to prevent the bath curtain from being displaced from its proper operative position while the shower is in use.

The currents of air produced by the water spray discharged from shower-bath heads act on the suspended curtain of the shower bath to displace it and result in discomfort and annoyance, the curtain frequently becoming wrapped around the bather. Such displacement of the comparatively light curtain occurs in different ways depending on the arrangement of the rod from which the curtain is suspended, the proximity and arrangement of the adjacent bath room walls, the location of the shower head, the force of the spray and other factors. The induced air currents frequently draw the curtain in against the bather, or may blow it out of the tub, and where more than one curtain is employed may separate the curtains at the overlapping parts thereof and permit leakage of water therewith.

My invention contemplates the provision of means for preventing the displacement of the curtain inwardly or outwardly of the tub or away from the adjacent curtain and the elimination of the discomfort and annoyance resulting therefrom, said means taking the form of rods suspended from the curtain rod and slideable thereon, and arranged to be locked against swinging movement and thereby to hold the curtain in its proper operative position.

My invention further contemplates the provision of simple and inexpensive means adapted to be employed with present shower curtain installations and also of means adapted for new installations for preventing the curtain from blowing about.

My invention further contemplates the provision of a shower-curtain holding installation comprising rods engaging the curtain and designed to be readily locked in place at their upper ends against swinging movement or movement other than sliding movement on the curtain rod on which the rods are suspended.

The various objects of the invention will be clear from the description which follows and from the drawing, in which

Fig. 1 is a perspective view of a shower bath and curtain installation showing a typical form of my invention applied thereto.

Fig. 2 is a fragmentary top plan of the curtain rod and of the curtain-holding means of Fig. 1.

Fig. 3 is a vertical section of the curtain rod showing the curtain-holding rod and the means for locking the latter rod in place on the curtain rod.

Fig. 4 is a rear view of the same.

Fig. 5 is a vertical section of a modified form of my invention wherein a curtain rod of non-circular cross-section is used.

Fig. 6 is a perspective view of one form of the curtain-holding rods showing sewing holes therein by means of which the rod may be secured to the curtain.

Fig. 7 is a perspective view of a curtain and of one of the curtain-holding rods showing the rod inserted into a pocket at an edge of the curtain.

Fig. 8 is a similar view showing the curtain-holding rod inserted in a pocket at the center of a curtain.

Fig. 9 is a horizontal section of a curtain-holding rod showing the curtain removably held thereto by a spring clip.

Fig. 10 is a front view of the same.

Fig. 11 is a horizontal section of the curtain-holding rod showing the spring clip holding the rod to a part of the curtain intermediate the side edges thereof.

My invention is applicable to all of the usual types of shower curtain installations using curtain rods, whether of the L-shaped, U-shaped, circular or straight line type, though I have shown my invention applied in Fig. 1 to the L-shaped type.

In the practical embodiment of the invention which I have shown by way of example, the L-shaped curtain rod 15, as is usual, is circular in cross-section and secured to the adjacent walls of the bath room in the usual manner. The usual curtain rings 16 sliding on the rod, removably support the curtains 17 and 18 which are intended to be overlapped at their adjacent edge portions. In connection with the usual installation of this nature, I have provided means for preventing the curtains from blowing inwardly or outwardly of the tub 19 or from blowing apart at the overlapped parts thereof.

As shown in Figs. 1 to 4 inclusive, said means takes the form of a plurality of vertical curtain-holding rods and one or more locking clamps mounted on the curtain rod 15 for preventing the holding rods from swinging on the curtain rod or from separating from each other when used at the adjacent edges of the adjacent curtains. The end holding rod 20 is preferably, though not necessarily, inserted in the vertical

pocket 21 at the edge of the curtain 18. Said pocket is formed by doubling back on itself the marginal part 22 of the curtain and securing it by stitching as 23 (Fig. 7). The pocket is preferably left open at the top for the insertion of the rod. At its upper end, the rod is bent into a generally U-shaped open hook 24 embracing the curtain rod 15 and terminating in an inwardly bent part 25 to limit the distance which the rod 20 may be raised ordinarily above the curtain rod. A roller as 26 is mounted in horizontal position on the hook for free rotation thereabout, said roller rolling on the curtain rod as the holding rod 20 is moved along said curtain rod. Preferably, the holding rod is made just long enough to extend slightly past the top of the tub, but not to extend too far into the tub. A part 27 of the hook portion 24 is flattened or otherwise reduced in thickness or diameter in order that the rod 20 may be removably clamped or locked in the clamp 28.

Said clamp preferably comprises the band 29 having outstanding, perforated, flanges 30, 31 through which is passed the bolt 32 for adjustably tightening the clamp on the curtain rod. The rod-receiving clip 33 is secured in a transverse position to the band and is provided with the spaced cylindrical rod-holders 34 and 35, each having an opening as 36 at its side. The inner diameters of the holders 34 and 35 are each about the same as the unreduced part of the rod 20 or hook 24.

When the rod 20 is to be clamped in position, its hook portion 24 is moved along the curtain rod 15 until it reaches a position between the members 34 and 35 of the clamp 28. The rod is then raised and also moved along the clip 33 to carry the reduced portion 27 through the open side of and into one of the holders 34 or 35, the bent portion 25 preventing the hook from being lifted off the rod 15. After the reduced part 27 has entered the clamp member, the rod is dropped thereby carrying the unreduced hook part which is above the part 27, into the holder and locking the rod and the curtain engaged thereby against movement relatively to the curtain rod, except a deliberate lifting movement to disengage the upright rod from the clamp.

A rod 37 similar to the rod 20 may be inserted in the pocket 38 at the edge 39 of the curtain 18, a clamp 42 being arranged on the curtain rod 15 at the proper point to lock the rod when the curtain is stretched into its operative position as shown in Figs. 1 and 2. In said position, the curtain 18 is below and is drawn past the holder 35. The rod 37 when lowered is held by the holder 34 of the clamp. To open the curtain, the rod 37 is lifted to bring its reduced part 27 adjacent the side opening in the holder 34 whereafter the rod is withdrawn transversely from the clip 33 and slid along the curtain rod to the left end thereof.

The curtain 17 is similarly provided with similar rods as 40 and 41 at its side edges. The rod 40 is drawn past the right-hand edge 39 of the curtain 18 to cause the curtain 18 to overlap the curtain 17. Said rod 40 is then engaged with and locked in the holder 35 of the corresponding clamp 42 in the manner hereinbefore explained in connection with the rods 20 and 37. The rod 41 at the other side edge of the curtain 17 is similarly locked in the clamp 43 which is similar to the clamps 28 and 42 and hence need not be further described. The rods 40 and 37 being locked in their upright positions, the adjacent

edge portions of the curtains cannot separate to permit water to pass therebetween.

If, owing to the length of the curtain the edge rods in the curtains should prove to be insufficient to prevent the intermediate part of either curtain from blowing about, then as many additional rods as 46 and corresponding clamps as 45 may be provided as may be found convenient or desirable.

It will be understood that where a straight line curtain rod is used in place of the L-shaped curtain rod 15, a single curtain as 18 may be used, and only edge rods and end clamps normally employed. Where the curtain is of considerable length, however, or where the current of air is excessive, it may be advisable to employ the additional intermediate upright rod and a corresponding clamp. Where the curtain rod is U-shaped, two curtains similar to the curtain 17 are used with end clamps as 43 and 28 and an intermediate 20 clamps as 42, by means of which the adjacent edges of the curtains may be overlapped. Where a circular curtain rod is employed, the usual single curtain may be used with edge rods and end clamps, with or without an intermediate rod 25 and clamp as may be found desirable. Since curtain rods now in ordinary use are of circular cross-section, the fixed clamps as 28 and 42 serve to form a locking means for the upright rods adapted to be readily clamped in place on the 30 curtain rod in spite of its circular cross section, and from which the upright rods need seldom be disengaged.

In those cases where it is not desired to insert a curtain-holding rod in edge pockets or central pockets, (see Fig. 6) the rod as 46 may be provided with sewing holes as 47 at the desired intervals as by flattening a portion of the rod if desired, and piercing it, though it will be obvious that the sewing holes may be made in the rod 40 without flattening it. The curtain 18 may then be readily sewn to the rod by the stitching 48, passing through the sewing holes. To remove the rod, the stitching is severed and the curtain freed for laundering and the like. Should sewing prove objectionable in certain cases, the rod 20 may be secured to the edge portion of the curtain by bending the edge portion as 49 (Figs. 9 and 10) about the rod and securing the curtain in place on the curtain-holding rod as by means of a 50 suitable U-shaped spring clip as 50. A similar clip 50 may be used to hold the curtain-holding rod as 51 to any intermediate part of the curtain 18 by merely wrapping the curtain partly around the rod and passing the clip over the curtain and past the rod as will be readily seen from Fig. 11, the tendency of the clip sides to close holding the parts adequately together.

Referring now to Fig. 5, I have there shown an installation wherein the curtain rod 61 is of non-circular cross-section, preferably rectangular. The curtain rod is suitably supported as by means of the bracket 57 from the ceiling of the bathroom, so as not to interfere with the sliding operation of the curtain-holding rod 59. Said curtain-holding rod is similar to the rod 20 but the hook portion 60 thereof is shaped correspondingly to the curtain rod 61. The curtain holding rod cannot turn on the curtain rod by reason of the non-circular shape of the hook portion 60 thereof and of the curtain rod. The clamp 42 may be used to insure overlapping if more than one curtain is used. The rod 59 is preferably provided with the roller 26 adapted to roll on the curtain rod to permit easy sliding of the cur-

tain-holding rod from the open position of the curtain to the closed position thereof. The holders 34 and 35 of the clamps 28, 42 and 43 being on the inside of the curtain rod, the bather can 5 readily manipulate and lock and unlock the upright rods.

It will be seen from the above that I have provided a simple and inexpensive means adapted to be applied to shower-curtain rods now in use 10 and the curtains therefor, and also adapted for new installations, for preventing blowing of the curtains about either inwardly or outwardly, and preventing the edge portions of adjacent curtains from separating.

15 While I have shown and described certain specific embodiments of my invention, I do not wish to be understood as limiting myself thereto, but intend to claim the invention as broadly as may be permitted by the state of the prior art and the 20 scope of the appended claims.

I claim:

1. In a shower-bath curtain installation, a curtain rod, means for preventing displacement of the curtain from its operative position when 25 stretched into said position, said means comprising a plurality of upright rods, each terminating at its upper end in a curtain-rod-engaging portion slidably mounted on the curtain rod, means for detachably securing said upright rods to the 30 curtain, a clamp on the curtain rod for each of the upright rods, a reduced part on each of the upright rods adjacent the curtain-rod-engaging portion, and rod holders on the clamp having side openings therein and having an inner diameter

substantially equal to the unreduced portion of said curtain-rod-engaging portion, said curtain-rod-engaging portion preventing all movement of the rod except upward and disengaging movement thereof when the reduced portion of an 5 upright rod is passed through the side opening of a holder and then moved downward to arrange the unreduced part of the rod in said holder.

2. In a shower-bath curtain installation, a curtain rod, upright curtain-engaging rods, a bent 10 portion at the upper end of each of the upright rods slidably mounted on the curtain rod, a clamp for each of the upright rods fixed to the curtain rod, a rod-holding member on the clamp adapted to removably receive part of the bent portion, 15 and a reduced part on the rod below the bent portion entering the holder when the rod is lifted to permit sidewise withdrawal of the upright rod from the holder.

3. In a shower-bath curtain installation, a 20 clamp provided with means for fixing said clamp to a curtain rod, said clamp having a cylindrical member open at its top and bottom and open at one side thereof, said clamp being adapted to hold a curtain-engaging rod, and an upright curtain-engaging rod having a bent portion at its upper end slidable on the curtain rod and having a reduced portion below the bent portion, said reduced portion being of lesser thickness than the width of the side opening of the rod-holding 25 member and the top and bottom openings of said member.

JACK SHERMAN.
